UNITED STATES PATENT OFFICE.

J. H. BOYD, OF BALTIMORE, MARYLAND.

SADDLE.

Specification of Letters Patent No. 30,118, dated September 25, 1860.

To all whom it may concern:

Be it known that I, J. H. Boyd, of Baltimore, in the State of Maryland, have invented a new and Improved Mode of Making Rolls to the Cantle of Saddles; and I do hereby declare that the following is a full and exact description thereof, reference being had to the accompanying drawings and to the letters of reference marked thereon.

10 The nature of my invention consists in providing the cantle of a saddle with an india rubber roll, substantially as will be hereafter described.

15 To enable others skilled in the art to make and use my invention, I will proceed to describe its construction and operation. I construct my roll on any of the known forms of saddle-trees, but more generally to a 20 Somerset tree.

Figure 1, is a perspective view of a saddle-tree, strained in the usual way, with the roll attached, A, A representing the tree and straining. That part marked B, represents an india rubber roll, molded in such 25 form as to fit on the cantle of the tree, to

which it is permanently secured by tacking it, both to the inside and outside of the cantle, or in any manner substantially the same. After the roll is thus put on, the 30 saddle is completed in the usual way of a leather or stuffed roll. This roll may be made of various sizes to suit the different size trees. I generally make it about an inch in thickness by an inch and a half wide, 35 rather oval, or egg-shaped, with a groove in the thin part which fits over the cantle of the tree. The length must be in proportion to the tree as in the case of a leather roll.

The advantage of this roll is, that it can 40 be put on in less time than in any other way; and, that it gives a broad elastic seat to a saddle.

What I claim as my invention, and desire to secure by Letters Patent, is—

45 The application to the cantle of saddles of an india rubber roll as herein described.

J. H. BOYD.
